(57) **CLAIM**

The ornamental design for a golf putter, as shown and described.

DESCRIPTION

FIG. 1 is a perspective view of the top, front and left side of the golf putter;

FIG. 2 is a front elevation view of the golf putter;

FIG. 3 is a right side elevation view of the golf putter;

FIG. 4 is a rear elevation view of the golf putter;

FIG. 5 is a left side elevation view of the golf putter;

FIG. 6 is a top plan view of the golf putter; and,

FIG. 7 is a bottom view of the golf putter.

Any broken line illustration of environmental structure in the drawings is for illustrative purposes only, and forms no part of the claimed design.
